UNITED STATES PATENT OFFICE.

LUDWIG WILKENING, OF HANOVER, GERMANY.

MOTOR-CAR SEAT.

1,025,038.

Specification of Letters Patent.

Patented Apr. 30, 1912.

Application filed February 15, 1910. Serial No. 543,999.

To all whom it may concern:

Be it known that I, LUDWIG WILKENING, a citizen of the German Empire, and residing at Hanover, German Empire, have invented certain new and useful Improvements in Motor-Car Seats, of which the following is a full, clear, and exact description.

Hitherto the seats of motor cars have usually consisted of fixed seats provided with more or less yielding cushions. This class of seats, although providing to a certain extent for vertical jolting or vibration does not take into account the forward and rearward jerks or shocks or the lateral throw of the body in traversing sharp curves or in turning curves at a high speed.

The object of the present invention is to provide a motor car seat, which is supported to yield in all directions thus reducing the vibration transmitted to the persons on or in the car, to practically *nil*.

In order to render the present specification easily intelligible reference is had to the accompanying drawings in which similar letters of reference denote similar parts throughout the several views.

Figure 1 is a view of the seat in side elevation, a portion of the body of the car being shown in dotted lines. Fig. 2 is a top plan view showing two seats adjacent to one another, the cushions being removed.

Referring to the drawings in detail, *a* and *b* indicate cross bars which are carried yieldingly by the curved supporting member *h* secured to the floor, member *h* being supported on a spring frame or member *g* which may be advantageously made of thin flat steel or other suitable material. The yield-

ing members *g* are suitably mounted in the car and support the curved supporting member *h*, the curve of member *g* corresponding with the curve of a portion of member *h*.

The seats may be provided with cushioned arms *i*. At one side the seats are supported by resilient members *l* suitably connected with brackets *m*. If girths straps or strips are employed a piece of fabric is advantageously placed over the same to receive the cushions. The ends of the cross bars *a* and *b* might also be mounted in wound or helical springs, so that the whole seat would yield in every direction.

In addition to the obvious advantages of a car seat of the above described construction it tends to considerably decrease the danger of traveling in that the yielding nature of the seats, in case of a collision, will save the knees of the persons sitting backward which are the parts most subjected to injury.

I claim as my invention:—

In a seat, a plurality of curved supporting members, a plurality of cross bars connected therewith, a supporting spring located beneath one of said supporting members and curved to correspond therewith, an additional supporting device cooperating with the spring, and flexible means connecting the cross bars.

In testimony whereof I affix my signature in the presence of two witnesses.

LUDWIG WILKENING.
